GRAIN SEPARATING MACHINES AND ANTI-
PLUG DEVICES THEREFOR

Robert K. MacGillivray, Hopkins, and Daniel R. Buckman, Excelsior, Minn., assignors to Superior Separator Company, Hopkins, Minn., a corporation of Delaware

Application January 9, 1959, Serial No. 785,920

3 Claims. (Cl. 200—61.21)

Our invention relates generally to power operated grain separating devices and more particularly to means for automatically rendering such machines inoperative under conditions wherein any one of the several grain discharge openings therein becomes plugged.

Machines of the type involved are conventionally powered by one large electric motor which is sized to operate the entire unit, and thence such motors are capable of exerting adequate power to destroy portions of the machine should a plugged condition occur in any one of their several discharge openings. Furthermore, many of the more conventional protective devices in the form of electric motor overload protection or clutches placed at or connected to the prime mover and properly sized to start, accelerate and overcome maximum machine loading will lack the sensitivity required to detect stoppages in local areas in time to prevent damage to the components in those areas.

The primary object of our invention is the provision of mechanical means whereby the entire machine will be automatically rendered inoperative under conditions where discharged grain, due to plugging, builds up adjacent any one of the several discharge openings in the machine.

A further object of our invention is the provision of a device of the class above described including a switch and control means therefor for each of the several discharge spouts, said control means being responsive to the pressure of grain accumulating in its associated discharge spout to render the entire machine inoperative.

A still further object of our invention is the provision of a device of the class immediately above described including switch operated vanes mounted for swinging movements in each of said discharge spouts toward and away from their respective discharge openings in said machine and each positioned out of the normal path of movement of material discharged from their respective discharge openings.

A further point to take into consideration in laying a background for our invention is the fact that such machines are required to operate in an explosive atmosphere containing grain dust and that therefore such protective devices must afford a maximum of safety. With this in mind, a further object of our invention is the provision of devices of the type above described which afford a maximum of safety in their operation.

A further object of our invention is the provision of devices of the type above described which incorporate a minimum of working parts and which are relatively inexpensive to produce.

A further object of our invention is the provision of a device of the class described wherein the switch operating vane is mounted in a housing having opposite side wall portions which prevent grain from accumulating behind said vane, whereby to assure rearward swinging movements of said vane to actuate said switch under plugged conditions.

A further object of our invention is the provision of

2

a device of the class immediately above described in which said housing includes a perforate front portion exposing said vane to material accumulating in said spout, but limiting swinging movements of said vane toward said discharge opening.

A still further object of our invention is the provision of a device of the class above described in which said housing defines an opening in the lower end thereof for gravity release therefrom of grain entering therein through said perforate front wall under abnormal accumulation of grain in said spout.

A still further object of our invention is the provision of a device of the class above described which is positive in its operation and foolproof.

The above and still further objects of our invention will become apparent from the following detailed specification, appended claims and attached drawings.

Referring to the drawings wherein like characters indicate like parts throughout the several views:

Fig. 1 is a perspective view of a conventional grain separating machine incorporating our invention;

Fig. 2 is an enlarged fragmentary view in side elevation of one form of our invention, some parts being broken away and some parts shown in section;

Fig. 3 is a view partly in horizontal section and partly in top plan as seen from the line 3—3 of Fig. 2, some parts being broken away;

Fig. 4 is a fragmentary view in side elevation of one of the discharge hoppers of the machine of Fig. 1, showing a modified form of our invention, some parts being broken away and some parts shown in section;

Fig. 5 is a view in front elevation as seen from the line 5—5 of Fig. 4, some parts being removed and some parts being broken away;

Fig. 6 is a view partly in plan and partly in horizontal section as seen from the line 6—6 of Fig. 4, some parts being removed; and

Fig. 7 is a view in side elevation showing a modified form of mounting bracket for the control device of the instant invention.

Referring with greater particularity to the drawings, and initially to the structure of Figs. 1 to 3 inclusive, the numeral 1 indicates in its entirety a conventional power operated grain separating machine having a plurality of discharge spouts, only two of which are here identified by the numerals 2 and 3. As shown in Figs. 2 and 3, the spout 2 communicates at an upper end portion with a discharge opening 4 in the side wall 5 of the machine 1, and at its lower end with a vertically disposed depending discharge boot or leg 6.

Mounted within the discharge spout 2 for swinging movements on a horizontal axis 7 toward and away from the discharge opening 4 in the machine 1, is a vane 8. Specifically this is accomplished through the medium of a mounting bracket 9 secured to one side 10 of the spout 2, extending through a suitable opening therein and having a pair of vertically disposed laterally spaced flanges 11. A control switch 12 for the electrical drive motor, not shown, for the machine 1, is provided with a mounting stem 13 which extends through the mounting bracket 9, and which terminates at its inner end immediately below the pivotal connection 7 of the vane 8. An actuating plunger 14 for the switch 12 extends through the stem 13 and is yieldingly biased into engagement with the vane 8 by means of a coil compression spring 15 contained within the stem 13, in the usual manner.

Under the arrangement above described, when the discharge boot or leg 6 becomes plugged, for one reason or another, that portion of the processed grain discharged through the opening 4, will accumulate in the leg 6 until it reaches the level of the vane 8. At such a level, the pressure of the grain forces the vane 8 laterally out-

wardly or rearwardly on its pivotal connection 7, forcing the operating plunger 14 inwardly against the bias of the spring 15 to actuate the switch 12 and stop the electric motor, not shown but associated with and imparting power to the grain separator 1. Thus, the operations of the machine 1 are terminated before any accumulation of grain therewithin, and damage to the machine 1 from such accumulation is thereby avoided.

It might here be stated that because of the relatively small surface area afforded by the vane 8, the structure of Figs. 1 to 3 inclusive are particularly adaptable for use adjacent a discharge opening 4 wherein direct mechanical pressure on the processed grain is applied by means such as a screw conveyor, not shown.

In the structure of Figs. 4 to 7 inclusive, a slightly modified form of switch and actuator is utilized. As there shown, the box-like housing 16 is secured in an upright position in the hopper-like upper end 17 of the relatively larger discharge spout 3, through the medium of an angular bracket 18. As shown, the housing 16 has imperforate side wall portions 19 and an open front 20 which faces the laterally opening discharge aperture 21 communicating with the discharge spout 3 and is spaced laterally outwardly therefrom. As shown particularly in Fig. 4, a lip 22 extends laterally across the open front 20, for a purpose which will immediately hereinafter be explained.

Secured to the preferably imperforate back wall 23 of the housing 16 and projecting upwardly therefrom is a mounting bracket 24 which defines a pair of laterally spaced parallel mounting ears 25 which extend generally in the direction of the discharge aperture 21. Mounted for pivotal movements on a pivot pin 26 extending between the mounting ears 25 for swinging movements toward and away from the discharge aperture 21, is a vane 27, the lower end 28 of which extends into the housing 16 adjacent the open front end 20 thereof. As there shown, the extreme lower end 28 of the vane 27 engages the lip 22 and thereby limits swinging movements thereof in the direction of the discharge aperture 21.

The switch 12a is secured in operative position with respect to the vane 27 through the medium of a set screw 29 which locks the stem 13a within the horizontal bore 30 in the mounting bracket 24. The actuating plunger 14a is biased toward engagement with the vane 27, immediately below the pivotal connection 26 thereof by means of the coil spring 15a.

The operation of the structure of Figs. 4 to 7 inclusive is substantially identical to that of the structure of Figs. 1 to 3 inclusive, namely as the grain builds up in the discharge spout 3, due to stoppage or plugging of the discharge boot associated therewith but not specifically shown, when it reaches the level of Fig. 4, it enters the open front 20 of the housing 16 and forces the vane 27 rearwardly or laterally outwardly, thus actuating the plunger 14a against the bias of spring 15a to open the switch 12a and cut off the electric motor associated with and imparting power to the separator 1. In the structure of Figs. 4 to 7 inclusive, however, the side walls 19 of the housing 16 positively prevent the grain from accumulating rearwardly of the vane 27. Obviously such accumulation is undesirable in that it would prevent switch actuating movements from being imparted to the vane 27. It will be noted that the bottom of the housing

16 is apertured as at 31 to permit grain accumulating therein under abnormal-plugged conditions, to escape therefrom under the action of gravity when the discharge spout is unplugged.

Because of the greater surface area presented by the relatively larger vane 27, this arrangement has been found to be particularly adaptable for use adjacent discharge openings where no direct mechanical pressure is applied to the processed material discharged therefrom—the vane 27 being activated solely by the weight of the accumulating processed material.

In the slightly modified form of our invention shown in Fig. 7, means is disclosed for securing a housing 16 and associated anti-plug mechanism in closely spaced relation to a discharge boot 6a. As there shown, the angular mounting bracket 18a is secured to a mounting plate 32, the open front end portion 20 thereof extending through a suitable opening in the side of the boot 6a, so that the lower end portion 28 of the vane 27 will be exposed to accumulating grain in the boot 6a upon plugging thereof.

Our invention has been thoroughly tested and found to be completely satisfactory for the accomplishment of the above objects, and while we have shown a preferred embodiment thereof, we wish it to be understood that same may be capable of modification without departure from the scope and spirit of the appended claims.

What we claim is:

1. In a device of the class described, a power operated grain separator having an opening in one side thereof for discharge of processed material therefrom, a discharge spout communicating with said discharge opening, a control switch for said separator, means mounting said switch in close proximity to said spout, and switch actuator mechanism for said switch, said actuator mechanism including a vane mounted for swinging movements in said spout toward and away from said opening and positioned out of the normal path of movement of material discharged from said opening, linkage connecting said vane with said switch, means yieldingly biasing said vane toward said path of movement, said vane being responsive to the weight of discharge material accumulating in said spout to operate said switch against bias of said yielding means to render said machine inoperative, and a stationary housing for the lower end portion of said vane, said housing including opposite side wall portions one each spaced from an opposite side edge of said vane and which prevent grain from accumulating behind said vane.

2. The structure defined in claim 1 in which said housing includes a perforate front wall exposing said vane to material accumulating in said spout but limiting swinging movements of said vane toward said discharge opening.

3. The structure defined in claim 2 in which said housing defines an opening in the lower end thereof for gravity release therefrom of grain entering therein through said perforate front wall under abnormal accumulation of grain in said spout.
